(57) **CLAIM**

The ornamental design for an air excavator hose handle as shown and described.

DESCRIPTION

1. Air excavator hose handle
5.1 is a front, right side, perspective view of the air excavator hose handle;
5.2 is a back, right side, perspective view thereof;
5.3 is a right side elevational view thereof;
5.4 is a left side elevational view thereof;
5.5 is a back elevation view thereof;
5.6 is a front elevation view thereof;
5.7 is a bottom plan view thereof; and
5.8 is a top plan view thereof.

The broken lines in the drawings depict portions of the air excavator hose handle which form no part of the claimed design.
